UNITED STATES PATENT OFFICE.

HARVEY N. HARRISON, OF WASHTA, IOWA.

FARM WAGON.

Application filed February 2, 1925. Serial No. 6,247.

My invention relates to farm wagons, and it is my purpose to provide a wagon of unitary structure when assembled, and which is of simple, durable and inexpensive construction.

Another object is to provide such a unitary wagon in which the box is permanently fixed to the stringers, and which is especially suited for service about the outbuildings and barns of a farm, particularly in situations where it is desired to drive the wagon very close to the side of a building, or where it is desired to turn around in a short space.

More particularly, it is my object to provide a wagon in which the construction of the stringers and axle assembly is simplified and cheapened as compared with that of the ordinary wagon.

Another object is to provide a wagon in which the ends of the stringers serve as steps to aid the operator in getting into and out of the wagon.

Another object is to provide a simplified tongue and hound construction for the wagon.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a perspective view of the wagon.

Fig. 2 is a plan view of the wagon, the box being shown in phantom view by means of dotted lines.

Fig. 3 is a detail sectional view of the rear axle construction, taken on the line 3-3 of Fig. 2.

Fig. 4 is a detail sectional view of the same taken on the line 4-4 of Fig. 3.

Fig. 5 is a detail sectional view of the front axle and hound construction, taken on the line 5-5 of Fig. 2.

Fig. 6 is a detail sectional view of the same, taken on the line 6-6 of Fig. 5.

Fig. 7 is a detail sectional view of the same, taken on the line 7-7 of Fig. 2.

Fig. 8 is a detail sectional view of the same, taken on the line 8-8 of Fig. 7.

Fig. 9 is a detail sectional view of a portion of the wagon box construction, taken on the line 9-9 of Fig. 1.

Fig. 10 is a detail view illustrating the axle and draw bar connections.

In constructing my wagon a rear axle, 10, of wood or squared steel is used and provided at its ends with the rear wheels, 11. The front axle, 12, is similar to the rear axle with the exception of the ears, 13, which are formed integral therewith near the ends thereof, as illustrated in Figs. 7 and 8. The front wheels, 14, are preferably of smaller diameter than the rear wheels, 11. Supported on the axle, 12, is what I will call the saddle, 15, of the front axle construction. The saddle, 15, is secured to the axle by means of bolts, 16, extended through openings in the ears, 13, and connected at their upper ends by yokes, 17.

The saddle, 15, is tapered from its central portion to its ends, and at its center is provided with a face parallel to the lower edge, to which is affixed a fifth wheel ring, 18. The ring, 18, has an integrally formed spoke, 19, positioned on its diameter, which is parallel to the saddle, 15, and which rests on the upper edge thereof. The ring, 18, is secured to the saddle, 15, by means of bolts, 20, shown in dotted lines in Fig. 6, having beveled heads, as indicated, and extending centrally through the saddle from the upper to the lower edge thereof.

A brace, A, having the flat horizontal arms, 21, and the upwardly and outwardly inclined arms, 22, radiating from a common center, is fixed to the lower edge of the saddle, 15, by means of bolts, 20. In order to space the ends of the bolts away from the axle, 12, the saddle, 15, is slotted at 23 and the arms, 21, bent upwardly at 24 within the slots, 23. Bolts, 25, having countersunk heads, secure the ends of the arms, 22, to the ring, 18, at the front and rear thereof. The brace, A, serves to rigidly connect the saddle and fifth wheel ring into a unitary and sturdy construction.

Centered on the spoke, 19, is a stud, 26, having a lug, 27. An upper fifth wheel ring, 28, is provided having a diametric spoke, 29, in the center of which is a key-hole slot, 30, adapted to receive the stud, 26, when the two rings are in the proper relative positions. To the upper face of the ring, 28, are secured the pillow blocks, 31, which are inclined forwardly and toward each other as indicated in dotted lines in Fig. 2.

Rear axle brackets, B, are provided with sockets, 32, to receive the rear axle, 10, and with sockets, 33, substantially perpendicular

to the sockets, 32, to receive the stringers, 34. The stringers, 34, are of wood and of substantial size, as shown.

The sockets, 32, are provided at opposite corners with the spaced lugs, 35, and the sockets, 33, are provided at opposite corners with the similar spaced fingers, 36, extending, however, at right angles to the fingers, 35. The sockets, 32 and 33, being each of less width than length, the fingers, 35 and 36, may be positioned on the sides thereof with the slots therebetween vertically aligned to receive the U-bolts, 37, extending under the axle, 10, and securing at their upper ends yokes, 38, which engage the upper edges of the stringers, 34, in slots, 39, sunk into the upper edges of the stringers. By tightening the nuts, 40, which secure the yokes, 38, in place, the entire assembly just described may be drawn into a rigid unit.

Braces, 41, are provided with loops, 42, which receive the U-bolts, 37, and are secured between the U-bolts and the axle, 10. The braces, 41, extend diagonally forward and upwardly, and are secured at their upper ends to the stringers, 34, by means of bolts, 43.

Before proceeding, it may be mentioned that in assembling the wagon the braces, 41, are first slipped over the U-bolts, 37, the axle, 10, then being slipped between the arms thereof, and the brackets B, positioned between the arms of the U-bolts with the lower lugs in proper position receiving the arms thereof and then moved downwardly until the socket, 32, engages the axle, 10. The upper ends of the U-bolt arms may then be sprung into place between the lugs, 36, and the stringers, 34, placed in position.

The forward ends of the stringers are secured to the pillow blocks, 31, by means of the bolts, 44, having heads countersunk into the upper ring, 28, as indicated in dotted lines in Figs. 5 and 6. The keyhole slot, 30, is so positioned that the front axle must be turned through 180 degrees from the position shown in Fig. 2 in order to secure the upper and lower rings together. When the axle is returned to its normal position, the lug, 27, will secure the rings together so as to prevent them tipping relative to each other when a considerable pull is applied through the shaft to the front axle.

The wagon shaft, 45, is provided at its rear end with the rearwardly diverging draw bars, 46, having eyes, 47, linked into the eye bolts, 48, secured in the ends of the saddle, 15. Intermediate of their length the draw bars, 46, are flattened, as indicated at 49 in Fig. 5, to receive bolts, 50, securing the ends of a cross bar, 51, to the draw bars. The cross bar, 51, is bolted at 52 to the wagon shaft, 45, and thus a substantial hound construction is provided. It will be understood that the draw bars, 46, and the

eye bolts, 48, are of fairly heavy material to stand the wear and strain necessarily imposed upon them.

The wagon box, C, has the bottom, 53, secured to the floor joists, 54, by means of straps, 55, extending through the ends of the joists and upwardly along the sides, 56, of the wagon box. Spaced cleats, 57, at the front and rear ends of the side boards, 56, serve to receive the end gates, 58 and 59, respectively, and a rod, 60, is extended through the sides, 56, the inner cleats, 57, and the straps, 55, at the forward end of the wagon box and provided with a nut, 61. The rod, 60, serves to tighten the sides, 56, against the end gate, 58, to hold it in place.

A hook, 62, pivoted in an eye bolt, 63, secured in the inner cleat, 57, at the rear end of one of the sides, 56, is adapted to be hooked into an eye bolt, 64, secured in the other inner cleat, 57, to secure the rear ends of the sides, 56, against the end gate, 59. The hook, 62, may be unhooked from the eye bolt, 64, and supported by the eye bolt, 65, in inoperative position against the side of the wagon box.

The wagon box, C, is secured to the stringers, 34, by means of nails, 66, extending through the joists, 54, and into the stringers, 34.

It will be seen from the foregoing description that my wagon is, when completely assembled, a rigid unit.

The wagon is designed to serve as a handy wagon around a farm, and may be used for many odd jobs for which a farmer would not care to utilize a more expensive wagon.

It will be noted, as illustrated in Fig. 2, that the hubs of the wheels, 14 and 11, do not extend beyond the sides of the wagon. The farmer in driving adjacent the buildings of his farm or close to a feed rack will thus not be troubled by the wheel hubs catching against an object.

The stringers, 34, are so inclined and so positioned that they are spaced apart above the front axle a distance substantially sufficient to properly space the pillow blocks, 31, for proper securing to the fifth wheel ring. This is illustrated in Fig. 2. At the same time the rear ends of the stringers are spaced apart sufficiently to provide a steady foundation for the wagon box and a firm connection with the rear axle. Further, the forward ends of the stringers come together at a point somewhat ahead of the front of the wagon so as to provide a step for the operator in climbing into the wagon.

It may be mentioned here that the forward ends of the stringers are secured together by bolts, 67, extending therethrough.

The rear ends of the stringers extend beyond the rear of the wagon, as shown in Fig. 2, to provide steps.

In view of the uses to which the wagon

is especially adapted, it is not necessary that the wagon box be removable, and the construction shown is therefore satisfactory and much simpler and less expensive than the ordinary wagon construction. Should it be desirable to repair the wagon, the construction is such as to permit ready repairment of a part. For instance, the brackets, B, may be readily removed without interfering with the rest of the wagon assembly, by removing the nuts, 40, and simply drawing the U-bolts, 37, downwardly. By lifting up slightly on the stringer, 34, the brace may then be removed.

15 My wagon is especially fitted for feeding purposes around the barns of a farm. Some changes may be made in the construction and arrangement of the parts of my invention without departing from the 20 real spirit and purpose of my invention, and it is my intention to cover by my claims any modified forms of structure or use of mechanical equivalents which may be reasonably included within their scope.

25 I claim as my invention:

1. A farm wagon including a pair of stringers secured together at their forward ends and spaced substantially apart at their rear ends, a pillow block secured to each 30 stringer and spaced from the forward end thereof, an upper fifth wheel ring secured to said pillow blocks by bolts extending through the periphery of the ring through the pillow blocks and through the stringers, 35 a front axle assembly having a lower fifth wheel ring engaging said upper fifth wheel ring, and a rear axle assembly secured to the rear ends of the stringers.

2. A farm wagon including a pair of 40 stringers secured together at their forward ends and spaced substantially apart at their rear ends, a front axle assembly supporting the forward ends of the stringers, and a rear assembly supporting the rear ends of 45 the stringers, including axle brackets having sockets at their lower ends positioned to receive the axle and upper sockets positioned to receive the stringers, and means for securing the axle, the brackets and the 50 stringers together in rigid assembly.

3. A farm wagon including a pair of stringers secured together at their forward ends and spaced substantially apart at their rear ends, a front axle assembly supporting the forward ends of the stringers, and a rear assembly supporting the rear ends of 55 the stringers, including brackets having channeled sockets to partially receive the axle and upper channeled sockets disposed in directions substantially perpendicular to the aforesaid channeled sockets, and adapted to receive the lower edges of the stringers, and means for securing the axle, the brackets and the stringers together in 60 rigid assembly.

4. A farm wagon including a pair of stringers secured together at their forward ends and spaced substantially apart at their rear ends, a front axle assembly supporting the forward ends of the stringers, and a 70 rear assembly supporting the rear ends of the stringers, including brackets having channeled sockets to partially receive the axle and upper channeled sockets disposed in directions substantially perpendicular to the aforesaid channeled sockets, and adapted to receive the lower edges of the stringers, and a U-bolt extending around the axle and upwardly on either side of each bracket and around the upper edge of its respective stringer.

5. A farm wagon including a pair of stringers secured together at their forward 85 ends and spaced substantially apart at their rear ends, a front axle assembly supporting the forward ends of the stringers, and a rear assembly supporting the rear ends of the stringers, including brackets having channeled sockets to partially receive the axle and upper channeled sockets disposed in directions substantially perpendicular to the aforesaid channeled sockets, and adapted to receive the lower edges of the stringers, and a 90 U-bolt extending around the axle and upwardly on either side of each bracket and around the upper edge of its respective stringer, each bracket being provided with pairs of spaced lugs adapted to receive the arms of the respective U-bolts and position them securely relative to the bracket.

6. A farm wagon including a pair of 105 stringers secured together at their forward ends and spaced substantially apart at their rear ends, a front axle assembly supporting the forward ends of the stringers, and a rear assembly supporting the rear ends of the 110 stringers, including brackets having channeled sockets to partially receive the axle and upper channeled sockets disposed in directions substantially perpendicular to the aforesaid channeled sockets, and adapted to receive the lower edges of the stringers, a U-bolt extending around the axle and upwardly on either side of each bracket and around the upper edge of its 115 respective stringer, and braces having ends secured by the U-bolts adjacent the axle and extending forwardly and upwardly and secured to the stringers.

7. A farm wagon including a pair of 125 stringers secured together at their forward ends and spaced substantially apart at their rear ends, a front axle assembly supporting the forward ends of the stringers, and a rear assembly supporting the rear ends of the 130

stringers, including brackets having channeled sockets to partially receive the axle and upper channeled sockets disposed in directions substantially perpendicular to the aforesaid channeled sockets, and adapted to receive the lower edges of the stringers, and a U-bolt extending around the axle and upwardly on either side of each bracket and around its respective stringer, and provided 10 with a yoke engaging the upper edge of its respective stringer, and braces having ends provided with loops adapted to receive the U-bolts and to be engaged between the U-bolts and the axle, said braces extending forwardly and upwardly and being secured to the stringers.

8. A farm wagon including a pair of stringers secured together at their forward ends and spaced substantially apart at their 20 rear ends, an upper fifth wheel ring secured beneath the stringers adjacent the forward ends thereof, a front axle assembly including an axle, a saddle secured on the upper face of the axle, a fifth wheel ring secured 25 to the upper edge of the saddle midway of the ends thereof, a brace extending between the axle and the saddle and thence upwardly on either side thereof and secured to the periphery of the lower fifth wheel ring, and 30 means for pivotally connecting the rings together.

9. In a wagon construction, a front axle

assembly including an axle, a saddle secured to the upper face thereof, a fifth wheel ring secured to the upper edge of the saddle and 35 disposed centrally of the ends thereof, a bracket having arms extending longitudinally between the saddle and axle and bolted to the saddle by means of bolts extending through the fifth wheel ring, through the 40 saddle and through the ends of said arms, said bracket also having arms extending laterally of said first mentioned arms, and diagonally upwardly and outwardly, and secured to the periphery of the said fifth wheel 45 ring.

10. In a wagon construction, a front axle and hound assembly including an axle, a saddle fixed to the upper face thereof, a fifth wheel ring secured to the upper edge of the 50 saddle and positioned centrally of the ends thereof, a shaft, a pair of draw bars fixed to said shaft at a position spaced from the rear end thereof, said draw bars extending rearwardly and outwardly, and being pivotally secured adjacent the ends of the saddle, and a cross piece secured at its center to the 55 rear end of the shaft, and at its ends to the draw bars intermediate of their length.

Signed at Sioux City, in the county of 60 Woodbury and State of Iowa, this 26th day of January, 1925.

HARVEY N. HARRISON.
